[57] CLAIM

The ornamental design for a video telephone set, as shown and described.

DESCRIPTION

FIG. 1 is a top, front and right side perspective view of a video telephone set showing our new design; FIG. 2 is a top plan view thereof; FIG. 3 is a front elevational view thereof; FIG. 4 is a left-side elevational view thereof; FIG. 5 is a right-side elevational view thereof; and FIG. 6 is a rear elevational view thereof. The broken line showing of keys, lights, etc. is for illustrative purposes only and forms no part of the claimed design.
